UNITED STATES PATENT OFFICE.

JOHN C. BLACKHURST, OF CHORLEY, ENGLAND.

PRESSING ATTACHMENT FOR YARN-BEAMING MACHINES.

Application filed November 15, 1923. Serial No. 674,862.

To all whom it may concern:

Be it known that I, JOHN C. BLACKHURST, a subject of the King of Great Britain, residing at Chorley, in the county of Lancashire, England, have invented new and useful Improvements in Pressing Attachments for Yarn-Beaming Machines, of which the following is a specification.

This invention is an improvement on the 10 yarn-pressing means disclosed by Letters Patent of the United States granted December 5, 1922, to Richard Anderton and myself, No. 1,437,703.

The machine of said patent includes a 15 flanged beam, a longitudinally disposed drum rotated in connection with the beam, conical rollers bearing against the surface of the beam in proximity to the flanges thereof, and adjustable bearings carrying 20 said conical rollers, the object being to provide means whereby the yarn wound upon the beam is pressed to approximately the same extent close to the inner faces of the beam flanges as at other parts of the beam, 25 thus obviating certain disadvantages formerly experienced.

The chief object of the present invention is to simplify and reduce the cost of the 30 means for carrying the conical rollers and controlling the operation thereof.

Another object is to provide a pressing attachment, including said conical rollers, adapted to be installed as a unit independently of the usual parts of the machine.

I attain the above-mentioned and other 35 related objects by the construction herein-after described and claimed.

Of the accompanying drawings forming a part of this specification,—

Figure 1 is a view, showing in section, a 40 sufficient portion of a beaming machine, and in elevation a pressing attachment embodying my improvements.

Figure 2 shows in elevation a portion of 45 the machine and one of my improved attachments applied thereto.

Figures 3 and 4 are perspective views, showing the carrier and the standard herein-after described.

Figure 5 is a perspective view, showing 50 the complete attachment.

The same reference characters indicate the same parts in all of the figures.

In the drawings, 12 designates the usual 55 beam of a machine for beaming yarn, the beam being carried in bearings mounted on

levers 13, so as to rest on or be pressed into contact with the usual drum 14, the bearings allowing the beam to rise as its diameter is increased by the winding of yarn thereon. 60 The pressure between the yarn winding and the drum 14 causes the yarn to be tightly wound on the beam.

The machine includes the usual levers 15, carrying a foot-board 16, said levers and foot-board constituting the usual treadle, controlling the usual clutch and belt shift device, in a manner well understood in machines of this character.

As in the machine of the above-mentioned 70 patent, I make use of conical rollers 17, which are supported in such manner that the peripheries of said rollers may rest upon the ends of a winding of yarn on the roll, the larger ends of the rollers rotating in contact 75 with, or in close proximity to the flanges 12^a of the beam. The rollers exert pressure on the end portions of the winding, so that said portions are compacted, practically as closely as the intermediate portions of the 80 winding.

In carrying out my invention I provide 85 attachments, each including one of the conical rollers 17, said attachments being adapted to be installed independently of the machine and in such manner that the conical rollers may bear directly on the periphery of the beam 12, when the latter is empty, and may move outwardly from the beam as the winding of yarn increases in diameter. 90

My improved attachment comprises a 95 fixed standard 19, means for fixedly supporting the standard beside the drum 14, and adjacent to the outer side thereof, an oscillatory carrier 20, and a hinge connection between the upper end of the standard and the carrier, permitting movements of the carrier toward and from the beam, the conical roller 17 being mounted to rotate loosely on an arm or stud 21, fixed to the upper end of the 100 carrier.

The standard 19 is preferably attachable to a floor 22, independently of the machine, although, if desired, its lower end may be secured directly to a suitable portion of the 105 machine frame.

The standard is formed to project through the space between the treadle foot-board 16 and the outer side of the drum, said foot-board being in all cases spaced outward from the drum, as shown by Figure 1. In this instance, the standard is provided with 110

a base 23, adapted to be independently secured, as by bolts 24, to the floor. The standard is inclined above the base and its arrangement is such that it does not interfere 5 with either the drum 14 or the treadle.

The hinge connection between the standard 19 and the carrier 20, is preferably embodied in a pair of upstanding ears 24 and 25, fixed to the upper end of the standard, 10 and a hub portion 26 forming a part of the carrier, interposed between said ears and connected therewith by a pintle 27.

The carrier includes two arms, one projecting upward and the other downward 15 from the hub 26. The lower arm is provided with spring-engaging means, preferably embodied in oppositely projecting ears 28, adapted to engage the upper ends of helical springs 29, the lower ends of which are 20 engaged with anchoring means, such as hooks 30, fixed to the base 23.

The springs 29 act on the carrier to yieldingly press the conical roller 17 toward the beam.

25 I provide one-way clutch parts, carried by the standard and the carrier and adapted to permit an outward movement, and prevent an inward movement of the roller 17 relative to the beam, the arrangement being 30 such that the roller is adapted to bear on the beam when the latter is empty, and to be moved outward from the beam by a winding of yarn thereon.

Said clutch parts are preferably embodied 35 in ratchet teeth 31, formed on the ear 24, and a pawl 32 pivoted to the upper arm of the carrier 20, and adapted to engage either of the teeth 31, the pawl being preferably provided with a handle 33, whereby it may be 40 disengaged from the ratchet teeth.

It will be seen by reference to Figure 5, 45 that the attachment may be entirely self-contained, the springs 29 being secured to the carrier and to the base of the standard, so that all that is necessary to install the attachment, is to pass the standard through the space between the treadle foot-board and the drum, and bolt the standard base to the floor, although, as above stated, the standard 50 may be secured in any suitable way to a part of the frame of the machine.

It is obvious that two of the described attachments will be provided for each machine, the conical roller of one attachment 55 bearing on one end and the conical roller of the other attachment bearing on the opposite end of the drum, or the yarn winding thereon.

The conical roller may be moved outward 60 by hand from a completed winding on the beam, and retained by the one-way clutch out of contact with said winding.

I claim:

1. For use with a machine for beaming 65 yarns, which includes a rotary drum and a

flanged beam adapted to be rotated by the drum and movable from the drum by a winding of yarn on the beam; a pressing attachment comprising a standard, having means at its lower end whereby it may be 70 fixedly secured to a support below the beam and adjacent to the outer side of the drum, an oscillatory carrier, a hinge connection between the upper end of the standard and the carrier, permitting inward and outward 75 movements of the carrier toward and from the beam; a conical roller mounted to rotate loosely on the upper end of the carrier and adapted to bear on an end portion of a winding of yarn on the beam, at the outer 80 side of the latter, spring means acting on the carrier to yieldingly press the roller inward toward the beam, and one-way clutch parts carried by the standard and the carrier and adapted to permit an outward movement 85 and prevent an inward movement of the roller relative to the beam, the arrangement being such that the roller is adapted to bear on the outer side of the beam when the latter is empty, and to be moved forward and outward from the beam not only by a winding of yarn thereon, but also manually to separate it from said winding.

2. For use with a machine for beaming yarns, which includes a rotary drum, a flanged beam adapted to be rotated by the drum and movable from the drum by a winding of yarn on the beam, and a clutch-operating treadle projecting forward from the drum, the foot piece of the treadle being separated by a space from the drum; a pressing attachment comprising a standard formed to extend through said space without interference with the treadle, means for fixedly supporting the standard, an oscillatory carrier, a hinge connection between the upper end of the standard, and the carrier, permitting movements of the carrier toward and from the beam; a conical roller mounted to rotate loosely on the upper end of the carrier, and adapted to bear on an end portion of a winding of yarn on the beam, spring means acting on the carrier to yieldingly press the roller toward the beam, and one-way clutch parts carried by the standard and the carrier, and adapted to 100 permit an outward movement and prevent an inward movement of the roller relative to the beam, the arrangement being such that the roller is adapted to bear on the beam when the latter is empty, and to be moved outward from the beam by a winding of yarn thereon.

3. A pressing attachment substantially as specified by claim 1; the said standard being adapted to be fixed to a floor, and supported by the latter independently of the machine and the said spring means being connected with said carrier and the standard, so that the attachment is self-contained.

4. A pressing attachment substantially as specified by claim 1, the said one-way clutch being embodied in an ear fixed to the upper end of said standard and provided with ratchet teeth, and a pawl pivoted to said carrier and adapted to engage either of said teeth.

5. A pressing attachment substantially as specified by claim 1, said hinge connection being embodied in a pair of spaced apart ears, fixed to the upper end of said standard,

one of said ears having ratchet teeth, a hub forming a part of said carrier and interposed between said ears, and a pintle connecting the hub with the ears, the carrier including an upper arm carrying a pawl adapted to engage either of said teeth and a lower arm having spring-engaging means.

In testimony whereof I have affixed my signature.

JOHN C. BLACKHURST.
